UNITED STATES PATENT OFFICE.

ALFRED HARRINGTON, OF LEICESTER, ENGLAND, ASSIGNOR TO WILLIAM SPIERS,
OF LEICESTER, ENGLAND.

EDGE SETTING OR BURNISHING MACHINE.

No. 874,360.

Specification of Letters Patent.

Patented Dec. 17, 1907.

Application filed October 25, 1905. Serial No. 284,360.

To all whom it may concern:

Be it known that I, ALFRED HARRINGTON, subject of the King of Great Britain, citizen of Leicester, England, residing at Leicester, 5 in the county of Leicester, England, have invented certain new and useful Improvements in Edge Setting or Burnishing Machines, of which the following is a specification.

10 This invention relates to machinery employed in the manufacture of boots and shoes and has more particular reference to such machines as are used in the finishing operations of the said goods.

15 One of the principal objects of the present invention is to construct a machine in such a manner that the boot is automatically held with pressure against the operating tool thereby avoiding the necessity for the operator 20 to do it by hand.

In what are known as "edge-setting" machines for finishing or burnishing the edge of the sole of a boot or shoe the tool is carried in a very rapidly vibrating head or holder and 25 when the operator holds by hand the edge of the boot sole against the tool, the action of the latter gives a constant series of shocks or jars to the boot thus held, which vibratory shocks are communicated to the hands and 30 arms of the operator and prove very detrimental and soon incapacitate him to a more or less degree as is well known. An important advantage accruing from this invention is that the boot is held automatically by mechanical means against the tool and thus the 35 disadvantages to the operator above referred to are entirely obviated.

A machine constructed in accordance with this invention comprises a holder or carrier 40 for the boot and mechanism for automatically presenting or holding the boot to the operating tool and guiding it thereagainst so that it is maintained in constant contact with the tool until the operation is completed, 45 when the operator removes the boot and inserts another in its place. The holder or carrier is constructed in such a manner that the boot is gripped or clamped thereby and can be instantly released and placed in position 50 in the shortest possible time.

The carrier is supported and moved in relation to the finishing tool in both a longitudinal and lateral direction, the longitudinal movement taking each side of the boot past 55 the tool and the lateral movement causing

the toe of the boot to pass the tool. This compound movement is effected by means of two slides whose movements are in a horizontal plane at right angles to each other, derived from suitable intermediate mechanism between them and the driving shaft, the said slides having counterweights and springs or equivalent means arranged in connection therewith to insure the boot being held with sufficient pressure against the tool to overcome the resistance offered by the movement of the tool. The tool by which the finishing operation is effected may, if it be a circular tool, be carried on the end of a rotating or reciprocating vertical spindle having a constant position in relation to the carrier, and be operated from gearing between it and the driving shaft if a continuous rotary motion is required, or, by a crank and connecting mechanism with the driving shaft, if a reciprocating movement of the tool is preferable. The said two slides, by which the boot and its carrier or holder are carried, are operated by the following mechanism. The upper slide which actually carries the boot holder 80 is actuated by a series of levers and connecting rods or equivalent operated from a crank on a worm wheel driven by a worm on the driving shaft.

The lower slide or carriage in which the upper slide fits, receives its lateral motion from a lever operated directly from a driven shaft.

The invention will however be more clearly understood from the following further description with reference to the several sheets of drawings, in which:—

Figure 1., is a front elevation of a machine constructed according to this invention, the boot carrier in this figure, being removed so as not to obscure any of the parts. Fig. 2., is a sectional plan taken on the line a—a of Fig. 1 & showing the driving mechanism to the several parts. Fig. 3., is a sectional side elevation, and Fig. 4., is a plan taken on the line b—b of the said Fig. 3.. Figs. 5 & 6., are side and end elevations respectively of the boot carrier or holder & its slide detached from the machine. Figs. 7, 8 & 9., are diagrammatic views showing the boot holder in varying positions in relation to the finishing tool. Figs. 5 to 9 are drawn to a larger scale than the remaining figures and the same reference characters are used to designate like parts throughout the drawings.

The machine as illustrated in Figs. 1, 2, 3 & 4 comprises generally a main frame or stand 1 inclosing within the same all the driving mechanism and supporting on the top 5 thereof an arm 2 carrying the finishing tool and its driving gear, and the slides and guiding mechanism for holding and moving the boot round in contact with the said tool.

Carried in the lower part of the frame 1 is 10 a counter-shaft 3 provided thereon with a pulley 4 adapted to be constantly driven from any suitable source of power, and a second pulley 5 on said shaft is arranged to transmit by means of a belt 6 the motion to 15 a shaft 7 in the upper part of the frame and hereinafter referred to as the driving shaft. Fast and loose pulleys 8 & 9 are provided on the said driving shaft 7 to receive the belt 6 and in order that the machine may be 20 stopped when required, the belt being moved by any suitable means not shown connected therewith. The edge setting or finishing tool 10 is carried on the lower end of a vertical spindle 11 supported in the head 12 of the 25 arm 2 and a semi-rotating or oscillating movement which, in practice is found preferable, is imparted to the said tool and its spindle by the following mechanism. A spindle 13 vertically carried in the upright 30 part of the arm 2 is provided at the top with a crank 14 and has imparted to it a continuous rotary movement by means of gear wheels 15 & 16 driven from a wheel 17 on the driving shaft 7 (see Fig. 1). A wheel 18 on the lower 35 end of the spindle 13 is adapted to gear with the driven wheel 15, the crank 14 on the upper end of said spindle being connected by means of a connecting rod 19 to a crank pin 20 on the side of a sleeve 21 carried in the 40 head 12 and through which the tool spindle 11 passes. It will be obvious that, if the throw of the crank 14 is considerably less than that of the crank pin 20 on the sleeve, the former while being continuously rotated, 45 will only partially rotate the latter and a semi-rotatory or oscillating movement of the tool 10 will result.

The vertical spindle 11 is always driven by the rotation of the sleeve 21 but in order 50 to compensate for the rise or upward curvature at the waist of the sole edge of the boot as it is moved round the tool, the latter together with its spindle 11 is arranged so as to rise and fall vertically as the movement 55 and contour of the boot sole requires. This is effected by providing the tool spindle 11 on each side with a pin or stud 22 which projects through a slot 23 in each side of the driven sleeve 21, and a counterweight 24, 60 though not actually necessary, is preferably attached to the upper end of the tool spindle 11, by means of a chain 25 passing over small pulleys 26. The compound movement, necessary for carrying the sides and toe of the 65 boot round in contact with the tool 10, is

effected by means of two superposed slides 27 & 28 movable in a direction at a right angle to each other, as is clearly shown in Fig. 4. The upper slide 27 on which the boot is carried is positively operated backwards and forwards by means of a crank 29 attached to the upper end of a vertical spindle 30 carried in a bearing 31 on the frame of the machine, the said spindle being continuously rotated by means of a worm wheel 32 75 driven from a worm 33 on the driving shaft 7.

As will be seen in Fig. 4, connection is made between the slide 27 and crank 29 by means of a double slotted link 34 rigidly attached to rods 35 adapted to slide backwards 80 and forwards in bearings 36 supported on the top of the frame 1. As the crank 29 moves round its circular path, a roller 37 on a crank pin 38 moves laterally along the slot 39 of the link 34, causing the latter to slide backwards and forwards carrying with it the slide 27 which is connected to the said link by means of a roller 40, on a pin 41 on the slide, engaging a second slot 42 of the said link 34. In order that the length of movement of the 90 said slide 27 may be varied according to the size of boot to be finished the crank pin 38 is adjustable along the face of the crank 29 such adjustment being made by means of the screw 43. 95

The lower slide or carriage 28, in which the upper slide 27 is movably carried, is mounted on a bed 44 attached to or formed integrally with the upper portion of the frame 1 of the machine, and in order that the said slide 28 100 may move freely along its bed 44 it is provided with rollers or anti-friction bearings 45. The said slide 28 receives its lateral movement partly from the engagement of the edge of the boot sole with and movement 105 of the latter round the tool; and a lever 46 pivoted at 47 to the inside of the frame 1. The said lever 46 has an oscillating movement imparted to it by means of a cam 48 engaging a roller 49 on the lower end 50 of said lever, said cam being mounted on a shaft 51 carried in the frame of the machine and being constantly driven from a bevel wheel 52 on the vertical spindle 30 by means of intermediate gear wheels 53, 54 & 55 (see Figs. 115 2 & 3). The wheels 53 & 54 are mounted on a shaft 56 carried in the frame 1 and are all continuously driven from the driving shaft 7 through the medium of the worm and worm wheel 33, 32 before mentioned. 120

The movement of the edge of the boot sole round the tool 10 is such that as the slide 27 carrying the boot, is moved forward, the engagement of the said edge with the tool causes the lower slide 28 to move laterally away from the center of the machine as the wider part of the sole comes round to the side of the tool, and, in like manner as the slide 27 is moved backwards the gradual narrowing of the sole towards the toe, causes the 125 130

lower slide 28 to move in the opposite direction, *i. e.* towards the center, the edge of the sides of the sole being constantly held in contact with the tool and on either side of same 5 with a pressure greater than the resistance offered by the tool when in motion, by means of counterweights 57, 58 (Fig. 1) carried on bolts 59 which are connected to each side of the slide 28 by chains 60 passed over pulleys 10 61 carried on the fixed bed 44. Collars 62 provided on the bolts 59 are adapted to alternately engage fixed brackets 63 through which the bolts pass, that is to say as the lower slide 28 is moved by the action of the 15 sole edge passing round the tool 10, the weight on the side opposite to that in which the slide is moving, will be raised and constantly keep the said edge pressing against the tool and also draw the said slide back to 20 the center as the upper slide moves backwards. For instance when the slide 28 (Fig. 1) moves to the right hand side of the center, the weight 57 will be raised and the collar 62 of the opposite weight will rest upon the 25 bracket 63 and consequently allow the chain 60 of the weight 58 to become slack, until the said slide has moved back to its central position and towards the left hand when the weight 58 will rise and the opposite weight 30 57 remain out of action. It is found desirable however to give the slide 28 a definite movement across the central position when the toe of the boot passes in contact with the tool, and for this purpose the lever 46 before 35 mentioned is adapted to engage at its upper end a projection 64 on the underside of the said slide or carriage and, operated by the before mentioned cam 48, move the slide for such distance as may be required for the toe 40 of the boot to pass round the front of the tool.

It will be obvious that the movement of the crank 29 and lever 46 are so arranged and timed that the latter does not come into engagement with the projection 64 on the slide until the correct lateral position of the said slide has been reached and further that the formation of the cam 48 is such that a period of rest is given to the lever 46 at the end of 45 each stroke, to enable the projection 64 to move in front of the operating end of the said lever so that a definite movement of the slide 28 in both directions is attained.

It will be seen that while the lateral movement of the toe of the boot past the tool, (as just described) is taking place, it is essential that no forward movement should be imparted to the upper slide 27, and in order to prevent such movement the slot 42 in the 50 sliding link 34, as clearly shown in Fig. 4, is made wider in the center than at each end so that when the said link is moving backwards the roller 40 on the slide 27 will contact with the straight face 65 of the slot until the crank 55 29 reaches the forward extremity of its

stroke, when the definite lateral movement of the lower slide 28 will take place, the wide center of the link as the same commences to move forward again, allowing the roller 40 to remain free until the curved face 66 of the 60 said slot 42 comes into contact with it to pull the slide 27 forward, simultaneously as the definite lateral movement ceases. It is desirable however that the outer ends of the slot 42 should be approximately of the same 65 width as the diameter of the roller 40, in order that there may not be any loss of time in the reversing of the movement of the link 34 as the crank pin 38 passes the extremity of its backward stroke. The boot carrier or 70 holder, Figs. 5 & 6, preferably consists of a rest 67 provided at its forward end with an adjustable pad 68 to receive the toe and at the rear with a heel rest 69 which may be adjusted by means of a set screw 70 to vary the 75 angle of inclination of the boot relatively to the finishing tool. A lever 71 pivoted at 72 on the rest 67 is suitably shaped at its forward end to press on the upper at or near the toe of the boot to hold the latter in position, 80 said lever being raised from or pressed on to the boot by means of a screw 73 and hand wheel 74, the screw 73 passing through a nut 75 in the opposite end of the lever 71 and being pivoted at its lower end to the rest 67. 90 In view of the rise or upward curvature of the sole edge of the boot from the point where the waist proceeds from the forepart to the heel, it is necessary that the boot shall have a further movement than the movements hereinbefore referred to, otherwise the longitudinal movement leaves half or thereabouts of the thickness of the sole at the junction of the forepart and waist unfinished. To obviate this, a rocking or tilting motion is 100 105 imparted to the boot, as the same is moved forward, such motion being obtained in the following manner.

The rest or carrier 67 is pivotally attached to the upper slide 27 of the machine and provided on its under face with rollers 76 which project over and are adapted to engage cams 77 adjustably carried on the upper face of the lower slide 28. The rear end of the carrier 67 rests upon a clip shaped spring 78 110 115 which keeps the carrier in contact with the slide at its forward end, the opposite end of the spring being rigidly attached to the slide. As the slide 27 moves forward in the slide or carriage 28, the rollers 76 will ride up the cams 77 and consequently rock or tilt the boot and rest as illustrated in Figs. 8 & 9, and as will be clearly seen in Figs. 7 to 9, the combination of the rocking movement of the carrier and the rise and fall of the tool 10, as the boot is moved forward causes the tool to follow the variation in the contour of the sole edge and at the various points gives a universal relation between the said tool and boot. 120 125 130

The necessary pressure of the toe edge against the tool may be imparted by means of spring buffers 79 carried in the end of the slide 27 and arranged to make contact with a bracket 80 adjustably attached to the slide 28, and by compressing the springs on the buffers maintain the pressure of the tool against the sole edge. If desirable a number of tools and boot carriers may be arranged side by side, so that one operator may superintend the series, each separate carrier being provided with any well known separate clutch gear capable of being automatically thrown out of action at the moment each boot is completed.

What I claim then is:—

1. In an edge setting machine the combination with the finishing tool of a boot carrier provided with adjustable means for supporting the toe and heel respectively of a boot, means operable by a hand-wheel to hold said boot in position on the carrier, a slide to which the carrier is pivoted, cams fixed to a part of the machine and rollers on said carrier adapted to ride up the fixed cams to rock or vary the angle of inclination of the boot as the slide moves forward for the purpose described.

2. In an edge setting machine, the combination with a slide a boot carrier pivoted on the slide and adapted to be rocked as the latter moves forward, of a carrying head, a finishing tool adapted to rise and fall in said carrying head whereby said tool is caused to follow the contour of the edge of the sole of the boot as the latter is moved around and in contact with the same.

3. In an edge setting machine the combination with the finishing tool, of a slide, a boot carrier thereon comprising means for supporting and holding the boot and plungers on the slide adapted to be pressed against

a fixed part of the machine to keep the toe of the boot pressing in contact with the finishing tool substantially as described.

4. In an edge setting machine the combination with the finishing tool, of a boot carrier, a slide supporting the latter, a sliding link and rotating crank for moving the said slide backwards and forwards and a second slide on which the first slide is mounted, said second slide having movement at right angles to the movement of the first slide to cause the edge of a boot to move around in contact with the finishing tool for the purpose described.

5. In an edge setting machine the combination with the finishing tool of a boot carrier, a slide supporting the latter, a sliding link and rotating crank for moving the said slide backwards and forwards, a lower slide mounted on a fixed bed and weights or balancing means connected with said slide to maintain the sides of the edge of the boot in contact with the finishing tool as the lower slide moves laterally for the purpose described.

6. An edge setting machine comprising a tool, a fixed head carrying said tool, means for actuating the tool, a boot carrier, a slide carrying the same, a second slide carrying the first mentioned slide, a crank, a shaft, a worm and worm wheel connected with the crank and shaft for rotating the crank and connections from the crank to the slides for moving the same so as to cause the edge of a boot to move round in contact with the finishing tool.

In testimony whereof I affix my signature in presence of two witnesses.

ALFRED HARRINGTON.
